(57) **CLAIM**

The ornamental design for the miniature battery dispenser, as shown.

DESCRIPTION

FIG. 1 is a perspective view showing the front and top of the pusher for a battery dispenser of the present invention with the thumb slide in a forward and closed position;

FIG. 2 is a perspective view showing the front and top of the pusher for a battery dispenser of the present invention with the thumb slide in a rearward and open position;

FIG. 3 is a plan view of the top of the pusher for a battery dispenser of the present invention;

FIG. 4 is an elevational view of the front of the pusher for a battery dispenser of the present invention;

FIG. 5 is an elevational view of the rear of the pusher for a battery dispenser of the present invention;

FIG. 6 is an elevational view of a first side of the pusher for a battery dispenser of the present invention; and,

FIG. 7 is a plan view of the bottom of the pusher job for a battery dispenser of the present invention.

The first side elevational view shown in FIG. 6 is a mirror image of the opposite side of the pusher for a battery dispenser of the present invention. Those elements that are shown in the above drawings in phantom lines do not form a part of the design sought to be patented.
